UNITED STATES PATENT OFFICE.

SMITH GLOVER, JR., AND AMOS L. GLOVER, OF LONOKE, ARKANSAS, ASSIGNEES TO GLOVER TOOL COMPANY, OF LITTLE ROCK, ARKANSAS, A CORPORATION OF ARKANSAS.

BUSHING REMOVER.

Application filed November 22, 1926. Serial No. 150,095.

This invention relates to tools and has special reference to a tool for driving out hub bushings and bearing cups.

The principal object of the invention is 5 to provide, as a new article of manufacture, a novel tool for driving out the bushings used in automobile wheel hubs, the tool being constructed of a single length of rod metal, preferably steel, and round in cross- 10 section as well as being resilient in character; the length of rod being bent and forged to produce the particular tool.

With the above and other objects in view as will be hereinafter apparent, the invention 15 consists in general of certain novel details of construction and combinations of parts hereinafter fully described, illustrated in the accompanying drawings, and specifically claimed.

20 In the accompanying drawings like characters of reference indicate like parts in the several views, and:

Fig. 1 is a side elevation of the improved tool showing it in position for driving a 25 bushing out of an automobile wheel hub, the latter and its bushings being shown in section.

Fig. 2 is an edge view of the tool.

Fig. 3 is a section on the line 3-3 of 30 Fig. 1.

Fig. 4 is a section on the line 4-4 of Fig. 2.

Fig. 5 is a section of the tool only on the line 5-5 of Fig. 1.

Fig. 6 is a section on the line 6-6 of 35 Fig. 1.

Fig. 7 is a side view of a modified form of the invention using three prongs.

Fig. 8 is a section on the line 8-8 of 40 Fig. 7.

Fig. 9 is a side view of a second modification with four prongs.

Fig. 10 is a section on the line 10-10 of Fig. 9.

45 In the formation of this tool a suitable length of round steel rod is taken and bent centrally of its length as at 10 so that there is provided a pair of handle portions 11 which are circular in cross-section and which 50 contact throughout their length. At the bend these handle portions are forged as by hammering, pressing or other suitable shaping operation of like character, so that the combined cross-sections of the two por-

tions appear substantially rectangular. At 55 the same time the end at the bent portion is flattened as at 12 to form a striking surface for a hammer or other percussive implement. From the handle portions 11 the rod is continued forwardly and divergently, 60 the diverging portion adjacent the handle being forged to form a pair of flat spring portions 13 which are flatly rectangular in cross section with their wider surfaces opposed so that they can readily spring toward and from each other. Forward of the 65 spring portions 13 the rod is continued in its regular circular cross section and is then terminated at each end in an outwardly inclined terminal portion 14. The end faces 70 of these terminal portions are beveled at an angle to the axes of the portions, the beveling being such that the end faces lie in the same plane. Furthermore, the outer sides 75 of these terminal portions are flattened so that when the handle 11 is inserted through a hub and its bushing these flattened portions contact with the outer end of the bushing and form cam surfaces forcing the 80 terminal portions 14 together. These flat outer faces are indicated at 15 and the flat beveled forward faces at 16. It will thus be seen 85 that the tool thus constructed is an article of manufacture formed from a single length of rod forged and shaped to provide a highly efficient bushing removing tool.

In the form shown in Figs. 7 and 8 the tool is made by bending and forming a rod as in the form previously described but one of the spring portions 13 is formed, either by splitting or by welding a piece of the rod thereon, to provide a third spring portion 19 terminating in a portion 20 of the normal rod cross section and having an angularly disposed end 21. Obviously, the three 90 spring portions and their ends will be evenly spaced to lie 120 degrees apart as shown in Fig. 8.

In the form shown in Figs. 9 and 10 the tool is made in two parts, one part being termed the inner part and being identical in form and construction with the type shown in the first six figures of the drawing. The other or outer part is likewise formed from a single length of rod preferably of the same cross section as that from which the inner part is formed. This second length of rod is bent and forged to provide an impact 100 105

receiving head portion 22 and a pair of handle portions 23 which lie in the grooves between the portions 11. Opposite the spring portions 13 the second rod is flattened to provide spring portions 24 which terminate forwardly in portions 25 of the normal rod cross section and having angled ends 26 like the ends 15. In this case the outer portion has its legs disposed in a plane at right angles to the legs of the inner portion.

In each case it will be seen that the basic construction is that shown in the first form.

In operation, as indicated above, the tool is passed through the hub handle end first until the surfaces 15 engage the outer end of the bushing. Then the handle is grasped and the tool pulled further through the hub. The usual notches in the collars 16' of the hub 17' assist in guiding the tool and when the terminal portions 14 have passed inwardly behind the bushing 18 which it is desired to remove, they will spring out and the bevel faces 16 will engage the inner face of this annular bushing. Then by striking on the face 12 of the tool end with a hammer or the like the bushing 18 is quickly driven out.

There has thus been provided a simple and efficient device of the kind described and for the purpose specified.

Having thus described the invention, what is claimed as new, is:

1. A bushing driving tool consisting of a single length of resilient rod metal bent centrally of its length in an abrupt bend to form a handle portion consisting of two parts of the rod arranged in contact throughout their length, the parts adjacent the bend being formed into an end for receiving blows from a percussive implement and being substantially rectangular in cross-section, the rod being provided with portions extending divergently from the handle forming portions and flattened to produce spring sections flatly rectangular in cross-section with their wide sides opposed, the rod being continued beyond the spring sections in short lengths of the original cross-section, the rod further having outwardly bent extremities having end surfaces normally in the same plane and angularly disposed with reference to the respective axes of said terminal portions.

2. A bushing driving tool consisting of a single length of resilient rod metal bent centrally of its length in an abrupt bend to form a handle portion consisting of two parts of the rod arranged in contact throughout their length, the parts adjacent the bend being formed into an end for receiving blows from a percussive implement and being substantially rectangular in cross-section, the rod being provided with portions extending divergently from the handle forming portions and flattened to produce spring sections flatly rectangular in cross-section with their wide sides opposed, the rod being continued

beyond the spring sections in short lengths of the original cross-section, the rod further having outwardly bent extremities having end surfaces normally in the same plane and angularly disposed with reference to the respective axes of said terminal portions, the outer faces of the terminal portions being formed to provide flat surfaces acting as cams upon the insertion of the tool through a hub.

3. A bushing driving tool consisting of a single length of resilient rod metal bent centrally of its length in an abrupt bend to form a handle portion consisting of two parts of the rod arranged in contact throughout their length, the parts adjacent the bend being formed into an end for receiving blows from a percussive implement and being substantially rectangular in cross-section, the rod being provided with portions extending divergently from the handle forming portions and flattened to produce spring sections flatly rectangular in cross-section with their wide sides opposed, the rod being continued beyond the spring sections in short lengths of the original cross-section, the rod further having outwardly bent extremities having end surfaces normally in the same plane and angularly disposed with reference to the respective axes of said terminal portions; in combination with at least one more member diverging from the handle and having a spring portion and an end similar in form to the first-mentioned spring and end portions and permanently secured to the remainder of the tool.

4. A bushing driving tool consisting of a single length of resilient rod metal bent centrally of its length in an abrupt bend to form a handle portion consisting of two parts of the rod arranged in contact throughout their length, the parts adjacent the bend being formed into an end for receiving blows from a percussive implement and being substantially rectangular in cross-section, the rod being provided with portions extending divergently from the handle forming portions and flattened to produce spring sections flatly rectangular in cross-section with their wide sides opposed, the rod being continued beyond the spring sections in short lengths of the original cross-section, the rod further having outwardly bent extremities having end surfaces normally in the same plane and angularly disposed with reference to the respective axes of said terminal portions, the outer faces of the terminal portions being formed to provide flat surfaces acting as cams upon the insertion of the tool through a hub; in combination with at least one more member diverging from the handle and having a spring portion and an end similar in form to the first-mentioned

spring and end portions and permanently secured to the remainder of the tool.

5. A bushing driving tool consisting of a single length of resilient rod metal bent 5 centrally of its length in an abrupt bend to form a handle portion consisting of two parts of the rod arranged in contact throughout their length, the parts adjacent the bend being formed into an end for receiving blows from a percussive implement 10 and being substantially rectangular in cross-section, the rod being provided with portions extending divergently from the handle forming portions and flattened to 15 produce spring sections flatly rectangular in cross-section with their wide sides opposed, the rod being continued beyond the spring sections in short lengths of the original cross-section, the rod further having 20 outwardly bent extremities having end surfaces normally in the same plane and angularly disposed with reference to the respective axes of said terminal portions; in combination with a second length of rod 25 metal similarly bent and formed but having the two parts of its handle portion spaced to lie in the grooves between the two parts of the first handle portion and the bend overlying the doubled end portion of the 30 first rod, the free ends of the second rod lying in a plane at right angles to a plane passing through the free ends of the first rod.

6. A bushing driving tool consisting of a 35 single length of resilient rod metal bent centrally of its length in an abrupt bend

to form a handle portion consisting of two parts of the rod arranged in contact throughout their length, the parts adjacent the bend being formed into an end for receiving 40 blows from a percussive implement and being substantially rectangular in cross-section, the rod being provided with portions extending divergently from the handle forming portions and flattened to 45 produce spring sections flatly rectangular in cross-section with their wide sides opposed, the rod being continued beyond the spring sections in short lengths of the original cross-section, the rod further having 50 outwardly bent extremities having end surfaces normally in the same plane and angularly disposed with reference to the respective axes of said terminal portions, the outer 55 faces of the terminal portions being formed to provide flat surfaces acting as cams upon the insertion of the tool through a hub; in combination with a second length of rod metal similarly bent and formed but having the two parts of its handle portion 60 spaced to lie in the grooves between the two parts of the first handle portion and the bend overlying the doubled end portion of the first rod, the free ends of the second rod 65 lying in a plane at right angles to a plane passing through the free ends of the first rod.

In testimony whereof we affix our signatures.

SMITH GLOVER, Jr.
